US0D1066386S

(12) **United States Design Patent** (10) **Patent No.:** **US D1,066,386 S**
Kellogg (45) **Date of Patent:** **** Mar. 11, 2025**

(54) **DISPLAY SCREEN OR PORTION THEREOF WITH GRAPHICAL USER INTERFACE**

(71) Applicant: **Four Charm Technologies, LLC**, Birmingham, AL (US)

(72) Inventor: **Rawdon W. Kellogg**, Guntersville, AL (US)

(73) Assignee: **dSideAI, Inc.**, Boston, MA (US)

(**) Term: **15 Years**

(21) Appl. No.: **29/896,332**

(22) Filed: **Jun. 30, 2023**

(51) **LOC (15) Cl.** **14-04**

(52) **U.S. Cl.**

USPC **D14/496**

(58) **Field of Classification Search**

(57) **CLAIM**

The ornamental design for a display screen or portion thereof with graphical user interface, as shown and described.

DESCRIPTION

The FIGURE is a front view of a display screen or portion thereof showing a graphical user interface.

The outermost dashed broken lines of the FIGURE shows a display screen or portion thereof, and form no part of the claimed design. The remaining broken lines, where shown, also form no part of the claimed design.

1 Claim, 1 Drawing Sheet
